UNITED STATES PATENT OFFICE.

JOHN H. GOSS, OF WATERBURY, CONNECTICUT, ASSIGNOR TO SCOVILL MANUFACTURING COMPANY, OF WATERBURY, CONNECTICUT, A CORPORATION OF CONNECTICUT.

FUSE FOR PROJECTILES.

Application filed August 12, 1919. Serial No. 317,058.

To all whom it may concern:

Be it known that I, JOHN H. Goss, a citizen of the United States, residing at Waterbury, county of New Haven, and State of Connecticut, have invented certain new and useful Improvements in Fuses for Projectiles, fully described and represented in the following specification and the accompanying drawings, forming a part of the same.

This invention relates to certain improvements in fuses for projectiles.

In time fuses, the period of time between the firing of the projectile and its explosion is determined by varying the length of time which the charge of the fuse burns, that is, the burning period of the fuse charge is so calculated that the exploding charge of the projectile will be ignited a certain length of time after the projectile leaves the gun. It will be readily understood that accuracy in this burning period of the fuse is of great importance, particularly where the projectiles with which these fuses are used have high velocity, because obviously slight variations in the length of the burning period of the fuse result in wide variations in the position which the projectile occupies at the time of the explosion.

The object of this invention is to produce an improved time fuse in which the burning time or rate can be determined with a high degree of accuracy, so that uniformity in the time of explosion of the projectile is secured.

With this and other objects in view, the invention consists in certain constructions, and in certain parts, improvements and combinations as will be hereinafter fully described and then more fully pointed out.

Referring to the drawings which illustrate one embodiment of the invention,

Figure 1 illustrates, in side elevation, a time fuse embodying the improved construction.

Figure 2 is a vertical sectional elevation of the construction shown in Figure 1, on a somewhat larger scale.

In the concrete embodiment of the invention, which has been selected for illustration, 1 indicates the body of the fuse, the body being provided with a chamber in which the exploding charge 3 of the fuse is located, this chamber being closed by a screw cap 2, the body being also provided with a thread

4 by which the fuse is attached to the projectile. The body of the fuse is also provided with a shoulder 5 on which rests a ring 6, this ring containing a powder channel 7, a gasket 8 being interposed between the ring and the shoulder. An opening 10 is provided in the fuse body in which is located a powder plug 11, this opening registering with an opening 12 in the gasket 8. The ring is provided with an opening 13 in which a powder plug is located. Superposed upon the ring 6 is another ring 14 which is also provided with a powder channel 15 and a gasket 16 is located between the two rings, this gasket having an opening 17 which registers with the powder plug in the opening 13 in the lower, or, as it is usually termed, setting ring, this setting ring being provided with setting graduations 18, as shown in Fig. 1. The ring 6 is free to be rotated around the body of the fuse, but the upper ring 14 is prevented from rotation around the fuse, usually by being pinned to the body of the fuse.

The rings are fashioned to provide gas channels or flues, marked 19 and 19' respectively, these channels or flues being in communication through an opening 20. An opening 21 leads upwardly from the channel 19' in the ring 14. The rings are held in position by a screw cap 22 which is threaded to the body of the fuse, this cap being provided with flue or gas escape channel 23, which channel has passages 24 leading upwardly therefrom. In the particular fuse shown, the top of the cap 25 is of umbrella or mushroom shape, the openings 24 terminating under the overhang of the top.

The fuse is provided with the usual concussion primer 26 supported by a split ring 27, and with the usual firing pin 28.

In the operation of this fuse, which, as so far described, is of well-known construction, when the projectile is fired the set back causes the concussion primer to move back against the firing pin 28. This ignites the concussion primer which, through the opening 29, ignites a powder plug 30 and the plug in turn ignites the charge in the ring 15. This charge burns and ignites the powder plug in the opening 13, the flame passing through the opening 17 in the gasket 16, this ignition taking place earlier or later, according to the setting of the ring 6. This burning powder plug ignites the powder in

the channel ring 6 which burns and, through the opening 12 in the gasket 8, ignites the powder plug 10 in the opening 11 which ignites and explodes the charge 3 which causes the explosion of the projectile. As the charges in the rings burn, the generated gases are supposed to escape into the flues or channels 19, 19', and through the openings 20 and 21 into the flue or channel 23 and then out through the flues 24. The burning period of the fuse is determined by rotating the setting ring 6 to the desired point, as indicated by the graduations. This rotation of the setting ring 15 changes the position of the openings through which the flame of the burning charge in the upper ring is communicated to the charge in the lower ring and the burning of the charge in the lower ring is transmitted to the powder plug 11, and thus lengthens or shortens the amount of powder which must burn before the exploding charge in the fuse is ignited. The position 20 of the setting ring is effected by a suitable tool or wrench at the time when the projectile is loaded in the gun.

In fuses of this type, as heretofore constructed, the top cap 22 has been screwed down on the rings so as to force the rings together as tightly as possible and yet permit the positioning of the setting ring to be effected at the time the projectile is loaded into the gun. The cap, after having been thus screwed down, has been locked 35 in position, as, for instance, by a radial pin which extends through the wall of the cap and into the screw threads by which the cap was secured to the body.

In using projectiles provided with this fuse in antiaircraft guns, where a very high velocity of the projectile is attained, wide variations in the time of explosion were noted. It will be understood, of course, that the various channels or flue openings 40 in the fuse are so designed as to cause the gases developed to set up a certain gas pressure on the burning powder. Inasmuch as in the fuse construction described, the powder should burn at the determined rate which is, of course, influenced by the escape 45 of the generated gases, the variations in the time of explosion noted may be attributed to improper or unexpected escape of the burning gases. If, for instance, under the very great forces developed in firing, the rings are forced back against their gaskets, so as to unduly compress the gaskets, and the locked top cap cannot move on account 50 of the lock, a crevice or opening would open up between the top of the top ring and the lower edge of the top cap. Should this occur, the gases, instead of passing out through the flue openings in the cap 55 provided for them and through which it is designed and expected that they will es-

cape, would escape, to some extent, through the opening referred to which would be formed in the manner described between the top ring and the lower edge of the top cap. Should the generated gases escape 70 other than through the flues or channels provided for them, it will, of course, be understood that the gas pressure on the burning powder will not be that which the fuse is designed to effect, and, therefore, the 75 burning rate of the powder will vary.

According to the specific embodiment of the invention illustrated and described herein, the top cap, after being screwed down against the rings, as before described, instead of being locked, as by the radial pin referred to, is left free to turn down on the threads on the fuse body. The cap, therefore, under the great forces developed on the projectile in firing, and particularly the spin due to the rifling, is free to turn down and thus follow up any undue setting back of the rings. Crevices or openings between the lower edge of the cap and the top ring or between the rings cannot, therefore, be 80 formed and the gases developed by burning 85 will be compelled to traverse the flue passages provided for them. With this construction, therefore, the gas pressure in the fuse, during the burning of the charge, will be that which the fuse is designed to effect. At all events, it has been found in practical operation that projectiles equipped 90 with the fuse heretofore described and in which the top cap is left unlocked and free 95 to turn down under the force developed by the firing, explode with much greater uniformity as to time than is the case with fuses where the cap is locked as in former 100 constructions.

It is important that the cap should be locked against any reverse turning, that is, any turning which will cause it to move away from the rings. As has been pointed out, the usual practice is, after the fuse is loaded, to set the cap down so as to hold the rings so tightly that the setting ring can only be moved by the proper wrench or tool, and it is important that this relative position of the parts be maintained. While, in the improved construction, this may be effected in various ways, in the construction illustrated, the ring 14 is provided with a short recess 31 and the lower edge of the cap is provided with an integral projection 32 which engages that recess, this projection being formed by punching down the metal of the cap. The projection and recess are so related that when the parts of the fuse are assembled and the cap is screwed down to hold the rings, as above described, the shoulder 32 will bear against the rear shoulder 33 of the recess 31. With this construction, while the cap is free to turn to move down on the thread on the fuse 105 110 115 120 125 130

body, it cannot move in the reverse direction and, therefore, the parts of the fuse cannot loosen after assembling.

Constructions which embody the invention include means by which the parts of the fuse can automatically respond to the great forces developed at the time of firing the projectile in such a way as to prevent gas leaks, that is, to prevent the escape of the gases other than through the flues or channels provided for their escape. While this is effectively accomplished in the particular construction which has been heretofore described, it is to be understood that changes and variations may be made in this construction and that the invention is not, therefore, to be limited to the specific embodiment heretofore described.

What is claimed is:

- 20 1. A fuse including a body, a charge containing part carried by the body, said part having a flue through which the gases generated during firing may escape, and a cap carried by the body and provided with a gas escape flue, said cap being free to move under the forces developed during firing and by its movement maintain said flues gas tight throughout their length.
- 25 2. A fuse including a body, a charge containing part carried by the body, said part having a flue through which the gases generated during firing may escape, a cap also carried by the body and provided with a gas escape flue, said cap being free to move under the forces developed during firing and by its movement maintain said flues gas tight throughout their length, and means for locking the cap against movement in the reverse direction.
- 30 3. A fuse including a body, charge containing rings carried by the fuse, said rings being provided with gas escape flues, and a cap carried by the body and free to move toward the rings under the forces developed during firing.
- 35 4. A fuse including a body, charge containing rings, and a cap, said rings and cap being provided with flues through which the gases generated during firing may escape, and said cap being free to move toward the rings under the forces developed during firing and by its movement maintain said flues gas tight throughout their length.

5. A fuse including a body, charge containing parts mounted on the body, and a cap threaded on the body, said cap and parts being provided with gas escape flues, and said cap being free to turn down on its thread toward the charge containing parts under the forces developed during firing. 55

6. A fuse including a body, charge containing parts mounted on the body, a cap threaded on the body, said cap and parts 60 being provided with gas escape flues, and said cap being free to turn down on its thread toward the charge containing parts under the forces developed during firing, and means for locking the cap against movement in the reverse direction. 65

7. A fuse including a body, charge containing rings mounted on the body, one of said rings being rotatable on the body, a gasket between the rings, a gasket between 70 one of the rings and the body, and a cap threaded on the body, said cap and rings having gas escape flues, and said cap being threaded to the body and being free to turn down on the body toward the rings under 75 the forces developed during firing.

8. A fuse including a body, charge containing rings mounted on the body, one of said rings being rotatable on the body, a gasket between 80 one of the rings and the body, a cap threaded on the body, said cap and rings having gas escape flues, and said cap being threaded to the body and being free to turn down on the body toward the rings under the forces 85 developed during firing, and means for locking the cap against movement in the reverse direction.

9. A fuse including a body having a shoulder, two charge containing rings 90 mounted on the body, one of said rings being rotatable on the body, a gasket between the rings, a gasket between one ring and said shoulder, said rings having gas escape flues, a mushroom-shaped cap threaded on 95 said body and having gas escape flues terminating under the overhang of the cap, and said cap being free to turn down on the body toward the rings under the forces developed in firing. 100

In testimony whereof, I have hereunto set my hand.

JOHN H. GOSS.
